Augustus B. Stoughton
ATTORNEY.

UNITED STATES PATENT OFFICE

BRUCE FORD, OF PHILADELPHIA, PENNSYLVANIA

STORAGE-BATTERY COVER

Application filed June 30, 1925. Serial No. 40,492.

The principal object of the present invention is to provide a simple and comparatively inexpensive stopper structure for storage battery covers which is adapted to vent the storage battery and to oppose or prevent the escape of spray.

To these and other ends hereinafter stated, the invention includes a stopper comprising two heads of which one is a closure and baffle head and of which the other is a baffle head, and a stem holding said heads in spaced relation to provide an expansion chamber space between them, the closure and baffle head provided with a vent opening from said chamber past the closure, and the other of said heads providing an inlet to the expansion chamber restricted in area in respect to the area of the expansion chamber space.

The invention further comprises the improvements to be presently described and finally claimed.

In the following description reference will be made to the accompanying drawing forming part hereof and in which

Figure 1 is an elevational view of a stopper embodying features of the invention indicating also in cross section a part of a storage battery cover.

Fig. 2 is an inverted plan view of the stopper shown in Fig. 1, and

Figs. 3 and 4 are views similar to Figs. 1 and 2 illustrating a modification.

In the drawing, Figs. 1 and 2, the head, generally indicated at 1, includes a closure portion 2, and a baffle portion 3, and a threaded portion 4. The head 5 is a baffle head and is of less effective area than the baffle head 3. 6 is a stem holding said heads in spaced relation to provide between them an expansion chamber space 7, and it may be remarked that this chamber is enclosed, when the stopper is in use, by the internal wall of the neck A of the cover B. The closure and baffle head 1 is provided with a vent opening 8 from said chamber 7 past the closure 2 to the atmosphere. This vent opening is shown as a notch extending into the rim part of the closure 2 and into the threaded part 4, and it is not straight but crooked or angular. The head 5 provides an inlet 9 at its rim to the expansion

chamber 7 from the interior of the jar, and this inlet 9 is of restricted area in comparison with the area of the expansion chamber 7. The stem 6 is shown as oblong in cross section because that is a convenient shape for manufacture.

In use escaping gas carrying spray or vapor in passing through the inlet 9 attains considerable velocity which it loses in the expansion chamber 7 where the spray or vapor or liquid particles deposit from suspension in the gas and find their way back through the inlet opening 9. The gas devoid of spray or liquid particles escapes through the outlet 8 to the atmosphere, and the baffle portion 3 of the head 1 assists or plays a part in causing deposition of spray or minute particles of liquid from the gas as it escapes through the vent opening 8.

The construction and mode of operation of the modification shown in Figs. 3 and 4 are as above described except that the stem 6^a is shown as circular in cross-section instead of generally oblong and the baffle head 5^a more nearly approximates in size to the interior size of the part A of the cover, the periphery of the part 5^a being notched to provide an inlet 9^a diametrically opposed to the vent 8^a.

It will be obvious to those skilled in the art to which the invention relates that modifications may be made in details of construction and arrangement and matters of mere form without departing from the spirit of the invention which is not limited to those matters or otherwise than the prior art and the appended claims may require.

I claim:

1. A stopper for storage battery covers comprising two heads of which one is a closure and baffle head and of which the other is a baffle head, and is of less effective area than the closure and baffle head, and a stem holding said heads in spaced relation to provide an expansion chamber space between them, the closure and baffle head provided with a vent opening from said chamber space past the closure and the other of said heads providing an annular inlet to the expansion chamber space restricted in area in respect to the area of the expansion chamber space.

2. A stopper for storage battery covers comprising two heads of which one is a closure and baffle head and of which the other is a baffle head and is of less effective area than the closure and baffle head, and a stem holding said heads in spaced relation to provide an expansion chamber space between them and an annular entrance to that space, the closure and baffle head being provided with a peripheral notch constituting a crooked 10 vent opening.

BRUCE FORD.
